UNITED STATES PATENT OFFICE.

C. E. STELLER, OF GENESEE, WISCONSIN.

IMPROVEMENT IN SOD-CUTTERS.

Specification forming part of Letters Patent No. 36,245, dated August 19, 1862.

To all whom it may concern:

Be it known that I, C. E. STELLER, of Genesee, in the county of Waukesha and State of Wisconsin, have invented a new and Improved Sod-Cutter; and I do hereby declare that the following is a full, clear, and exact description of the same, reference being had to the accompanying drawings, making a part of this specification, in which—

Figure 1 represents a longitudinal vertical section of my invention. Fig. 2 is a plan or top view of the same. Figs. 3 and 4 are detached side elevations of the cutters. Figs. 5 and 6 are transverse sections of the same.

Similar letters of reference indicate corresponding parts in the several figures.

This invention consists in the arrangement of two or more vertically-adjustable cutter-beams, each being provided with a series of oblique cutters inclining laterally in opposite directions, in combination with a self-adjusting drag suspended from the rear end of the cutter-frame in such a manner that the sod is completely cut up by the action of the cutters, and the ground is pulverized and leveled by the action of the drag, ready to receive grass-seed or grain.

It consists, further, in the arrangement of notches in the top ends of the cutters, in combination with pivoted catches or buttons, in such a manner that by turning said buttons the cutters can be fastened or unfastened at pleasure.

To enable those skilled in the art to make and use my invention, I will proceed to describe its construction and operation with reference to the drawings.

The cutter-beams A B are adjustable in a vertical or upward-inclined direction between the guides a b, which are secured to the inner sides of the runners B', one opposite the other, as clearly shown in Figs. 1 and 2 of the drawings. When the cutter-beams are at their lowest position two or more blocks, a' a' x b' x b'', are inserted between the guides a b on the top of the beam and held down by pins a' b', which pass through the upper ends of the guides a b.

If it is desired to diminish the depth of cutting, the cutter-beams are raised, and one pair of the blocks a' x b' x is placed under each cutter-beam, while the other pair of blocks a' x b''

is retained above, and the thickness of these blocks is regulated so that by each pair of blocks a change in the depth of cutting of one inch is effected. For instance, if the full depth to which the cutters are made to cut is six inches, and it is desired to cut only four inches deep, two pairs of blocks have to be placed under each cutter-beam; or, if it is desired to cut only two inches deep, four pairs of blocks have to be placed under each cutter-beam, &c.

Each cutter-beam is provided with a series of cutters, C, which are inserted in an oblique direction and which incline laterally in different directions. The cutting-edges of each cutter stands at an angle of about forty-five degrees (more or less) toward a plane passing through the lower surfaces of the runners B', and one set of cutters inclines laterally toward one and the other toward the other side. By this arrangement each individual cutter passes easily through the ground, and if it meets with an obstruction—such as roots or stalks of corn, &c.—it cuts through the same with a drawing cut, or if it strikes a stone it pushes it on one side or passes readily over it; and by the combined action of the two sets of cutters every particle of ground between the two runners is cut up.

The two runners are connected in front by a cross-bar, E, and in the rear by a cross-bar, F, and from the front cross-bar an angular board, d, extends close to the front edge of the cutter-beam A. The object of this board is to prevent clods or other substances from lodging on the cutter-beam and between the same and the front cross-bar, E, and to deflect such clods downward and bring them in contact with the cutters.

G is the drag, which is suspended from hooks e on the rear end of the runners B'. This drag is provided with a double set of oblique scrapers, f f', one set being inclined in one and the other in the opposite direction, and with triangular ribs g extending from one side of the drag to the other. This drag, in passing over the ground, levels the same and leaves it in a perfect condition to receive grass-seeds or grain, or it may also be used for covering the seed.

For each machine two sets of cutters, C C', are provided, one set with sharp cutting-edges

and the other set with blunt rounded edges, as shown clearly in Figs. 5 and 6. These cutters are inserted into mortises in the cutter-beams, each cutter being provided with a shoulder, *h*, which bears against the under side of the beam, and with a notch, *i*, near its top end to receive a catch or button, *j*. These buttons are pivoted to the upper sides of the cutter-beams in such a position that they can be turned to catch in the notches *i* of the cutters, or so as to release the same, as may be desired. By this arrangement I am enabled to remove either one of the cutters whenever it may be desired, to sharpen the same or to replace it by another; or all the cutters may be taken out and replaced by a different set, according to the nature of the soil in which it is desired to use the machine.

The cutters *C*, with the sharp cutting-edges, are used in soft, marshy grass land, where they may meet with roots or stalks or other obstructions capable of being cut through by them; but in dry stony ground the cutters *C* are removed and the cutters *C'*, with the blunt cutting-edges, are inserted. By these means the cutting-edges are saved from injury when they come in contact with stones, and the dry ground is easily cut through by the blunt cutters.

A draft-chain, *H*, serves to draw the machine along through the ground. This chain is attached to hooks *k*, which are secured to the top edges of the runners *B'*, and it passes either through holes in the front cross-bar, *E*, or through loops projecting from the top edge of said cross-bar. By these means the pressure on the cutters can be regulated. When the draft-chain passes through the holes in the cross-bar the strain exerted on the machine is

in an upward direction and the pressure on the cutters is diminished, whereas, if the chain passes through the loops on the top edge of the cross-bar, the strain goes in a downward direction and the pressure on the cutters is increased. By this arrangement my machine can be made to work equally well in hard and in soft ground.

When it is desired to throw the cutters wholly out of the ground, the cams or shoes *I*, which are secured to ends of rock-shafts, *l* on the outside of the runners *B'*, are turned up by means of a hand-lever, *m*, and when the cutters are not to be used, and while the machine is moved from one field to another, the cutter-beams are turned upside down.

This machine can be used with equal advantage on dry or on marshy ground, and on account of the peculiar arrangement and position of the cutters it can be drawn along with a comparatively small expenditure of power.

Having thus fully described my invention, what I claim as new, and desire to secure by Letters Patent, is—

1. The arrangement of two or more vertically-adjustable cutter-beams, *A B*, each being provided with a series of oblique cutters, *C C'*, inclined laterally in opposite directions, in combination with the self-adjusting drag *G*, constructed and operating as and for the purpose shown and described.
2. The arrangement of the notches *i* in the top end of the cutters, *C C'*, in combination with the buttons *j*, as and for the purpose specified.

C. E. STELLER.
